Primary Examiner—Joel A. Sincavage*Assistant Examiner*—Anna K Dworzecka(74) *Attorney, Agent, or Firm*—Howard & Howard Attorneys, P.C.(57) **CLAIM**

The ornamental design for a magnetic holder for a tool, as shown and described.

DESCRIPTION

FIG. 1 is a perspective view of a magnetic holder disposed on a top of a tool,

FIG. 2 is a rear view; and,

FIG. 3 is a top plan view.

The phantom lines are environmental only and form no part of the claimed design.
